CLAIM

The ornamental design for a bathroom accessory post, as shown and described.

DESCRIPTION

FIG. 1 is a top perspective view of a bathroom accessory post, showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged detailed view of encircled area 9 shown in FIG. 1;

FIG. 10 is a perspective view of the bathroom accessory post, shown in a first environment of use;

FIG. 11 is a perspective view of the bathroom accessory post, shown in a second environment of use;

FIG. 12 is a perspective view of the bathroom accessory post, shown in a third environment of use;

FIG. 13 is a perspective view of the bathroom accessory post, shown in a fourth environment of use; and,

FIG. 14 is a perspective view of the bathroom accessory post, shown in a fifth environment of use.

The dash-dash broken lines illustrate portions of the bathroom accessory post that form no part of the claimed design. The dot-dash broken lines illustrate the border of the enlarged detailed view that form no part of the claimed design. All other dash-dash broken lines depict environment that form no part of the claimed design.

1 Claim, 14 Drawing Sheets
